[57] CLAIM

The ornamental design for a service counter, as shown and described.

DESCRIPTION

FIG. 1 is a front elevational view of a service counter;
FIG. 2 is a top plan view of the service counter of FIG.
1;

FIG. 3 is a rear elevational view of the service counter;
and

FIG. 4 is a right side elevational view of the service
counter.

The side of the service counter not shown is a mirror
image of the side shown in FIG. 4.
